MANUFACTURING COMPANY, A CORPORATION OF NEW JERSEY.

SEWING-MACHINE GUIDE.

1,248,841.

Specification of Letters Patent.

Patented Dec. 4, 1917.

Application filed February 13, 1914. Serial No. 818,448.

To all whom it may concern:

Be it known that I, GEORGE S. GATCHELL, a citizen of the United States, residing at Roselle Park, in the county of Union and 5 State of New Jersey, have invented certain new and useful Improvements in Sewing-Machine Guides, of which the following is a specification, reference being had therein to the accompanying drawings.

10 This invention relates to improvements for presenting to seam-covering stitch-forming mechanism a seam formed by overlapping and stitching together the marginal portions of the two plies of fabric designed 15 to be subsequently opened out to receive the covering seam for protecting the raw edges. The invention has for its object to facilitate the guiding of the work to the stitch-forming mechanism and the smoothing out and 20 stretching of the fabric upon opposite sides of the initial uniting seam in advance of the covering stitch-forming mechanism.

In its preferred form the improvement is applied to a cylinder-bed machine provided 25 with longitudinally acting feeding mechanism and with stitch-forming mechanism comprising a plurality of reciprocating needles and loop-taking means co-operating therewith in laying a covering thread 30 between the same crosswise of the direction of feed. According to the present invention, the work-supporting means are provided with an open-topped seam-guiding channel adapted to receive the overlapped 35 marginal portions of the fabric and having its delivery end or mouth flared outwardly and inclined backwardly and downwardly, in conjunction with a presser-foot having its toe portion flared and inclined correspondingly with the mouth of said channel to 40 which it is opposed. The seam-guiding channel may be formed by means of laterally and reciprocally adjustable guide-blocks secured upon the throat-plate or upon 45 the end-cap of a cylinder-bed machine in advance of the stitch-forming mechanism, the throat-plate having preferably formed therein a longitudinal slot in register with the seam-guiding channel and terminating 50 in an upwardly inclined groove extending beyond the needle apertures and beneath the forward end of a longitudinal groove or channel in the sole of the presser-foot extending from a point between the needle 55 apertures to the rearward end of the foot.

Heretofore it has been customary to provide a narrow channel in a member of or connected with the work-support to receive the overlapping marginal portions of the initially seamed fabric, and to provide the 60 presser-foot with a depending rib or keel entering the crease in the face of the fabric at the seam for guiding the same, as represented for instance in the U. S. Patent to G. E. Molyneux, No. 1,011,473 of December 65 12, 1911. While such guiding means have proved effective for certain classes of work, in connection with thinner and softer varieties of knit-goods their use has not resulted in the production of a sufficiently flat 70 seam, for the reason that the fullness drawn in at the initial seam by the action of the depending presser-foot rib in guiding the work to the stitch-forming mechanism was not disposed of before the penetration of the 75 needles in the work, thereby retaining the superfluous material at the seam and producing a slight rib or projection which in some cases has been found objectionable.

According to the present improvement, 80 not only are the opposed work-engaging faces of the throat-plate and presser-foot entirely flat at the stitching point, but the wedge-shaped nose of the presser-foot is adapted to serve as a smoothing and stretching element for the work by reason of the correspondingly flaring character of the mouth of the guide channel which holds the fabric at an inclination with the base of the throat-plate for engagement with the convergent smoothing faces of the presser-foot 85 nose or toe-portion.

In the accompanying drawings, Figure 1 is a perspective view of the forward portion of the cylinder-bed of a sewing machine provided with the present improvement, Fig. 2 a side elevation of the same with the throat-plate in section and one of the guide-blocks removed, and Fig. 3 a plan of the same with the presser-foot omitted. Fig. 4 is a perspective view of the throat-plate with the channel-forming guide-blocks applied thereto, and Fig. 5 a similar view of the presser-foot viewed from the under side. Fig. 6 is a perspective view showing a section of the 90 material adjacent the stitching point.

The type of machine to which the present improvement is preferably applied is that represented in the United States Patent No. 1,127,795, issued February 9, 1915. The 100 110

cylinder-bed constituting the work-support is shown composed of the tubular body portion 1 and the removable cylindrical end cap 2 which normally incloses the loop-taking means coöperating with the needles 3 carried by the reciprocating needle-bar 4. The top of the cylinder-bed is recessed to receive the arched throat-plate 5 having the flat work-supporting face 6 which is provided with the usual feed-dog apertures 7, the needle apertures 8 and intermediate tongue 9. The tongue 9 has in its face a groove 10 flared laterally and downwardly toward the front end of the machine and entering a longitudinal clearance slot 11 in the body of the throat-plate.

As represented in the drawings, the throat-plate has secured upon its forward end by screws 12 the spaced guide-blocks 13 with their parallel adjacent edges 14 affording the side-walls of an open-topped seam-guiding groove or channel directed toward the space between the needle apertures 8 and in alinement with the groove 10. The work-delivery portions 15 of the walls 14 are inclined divergently, backwardly and downwardly to meet the flat face 6 of the throat-plate at an obtuse angle, and the guide-blocks are adjustable toward and from each other by reason of the transversely elongated apertures through which the fastening screws 12 pass.

Opposed to the throat-plate adjacent the needle apertures is the foot-plate 16 of the presser-foot which is tiltingly secured by means of angularly disposed pivotal pins 17 and 18 to the lower extremity of the shank member 19 attached to the usual presser-bar 20, as more fully described in the United States Patent to G. E. Molyneux & G. S. Gatchell, No. 1,124,320, of January 12, 1915. The toe portion or nose of the presser-foot is wedge-shaped to form the convergent fabric-smoothing faces 21 having an angular relation to the flat lower face or sole 22 corresponding with that of the bearing-block faces 15 to the face 6 of the throat-plate. Intermediate the smoothing faces 21 is the guide-rib 23 adapted to enter the crease of the initial uniting seam. The substantially parallel walls 14 and work-delivery portions 15 of the spaced guide-blocks 13 thus form, with the nose or toe portion 23 and fabric-smoothing faces 21 of the presser-foot, a substantially Y-shaped seam-guiding channel. The foot-plate is provided with the usual elongated needle-apertures 24 and has extending from a point intermediate the same backwardly a longitudinal groove 25 supplementary to the throat-plate groove 10.

As represented in Fig. 6, the two pieces of knitted fabric *a* and *b* have their overlapped marginal portions *a'* and *b'* united by means 65 of the seam *c*. The fabric is introduced into

the machine opened out as represented in said figure, with the raw-edged marginal portions *a'* and *b'* entered in the channel 14, and with the crease at the seam in register with the dividing rib 23 between the smoothing faces 21 of the presser-foot. As the work advances lengthwise of the cylinder-bed under the action of the feeding mechanism, it is drawn over the divergent upper edges of the guide-blocks 13 and spread upon opposite sides of the initial seam by the smoothing faces 21 of the presser-foot in front of the needle, the overlapped margins *a'* and *b'* being drawn into the flaring mouth of the throat-plate groove 10 past the stitching point from which they are discharged through the registering clearance groove 25 in the bottom of the presser-foot, thereby receiving parallel lines of stitching *s* which are in practice connected upon the under side by the covering lower thread overlying the raw edges of the marginal portions *a'* and *b'* of the fabric. The guide-blocks thus afford divergent upper edges disposed materially above the face of the throat-plate which, together with the faces 15 of said blocks serve to maintain the fabric in contact with the smoothing faces 21 of the presser-foot, which maintains the fabric taut on both sides of the uniting seam and causes it to lie perfectly flat and uncomressed edgewise in receiving the covering stitches.

By laterally adjusting the guide-blocks, not only the parallel-sided guiding-channel but the divergent channels between the fabric-engaging faces 15 and 21 may be adjusted in width to accommodate fabrics of different thicknesses; and as these blocks are independently adjustable, they may be set for operation upon two pieces of fabric of different thicknesses and united as previously described along their overlapping edges. In the broader aspect of the present invention, it is obviously immaterial whether these blocks be made separate or integral and whether they be secured upon the throat-plate or some other part of the work-support such as the end-cap.

Having thus set forth the nature of the invention, what I claim herein is:—

1. In a sewing machine, in combination, a work-support, a pair of laterally spaced guiding elements projecting above the work-support to form an open-topped seam-guiding groove and having its delivery end backwardly flared and downwardly inclined, and a presser-foot having a continuous work-engaging surface the forward portion of which is backwardly flared and downwardly inclined and opposed to the downwardly inclined delivery ends of said guiding elements, thereby forming a continuous channel having opposed and outwardly flaring work-smoothing faces.

2. In combination, a throat-plate for sewing machines provided with a pair of laterally spaced guide-blocks forming an open-topped seam-guiding channel having its delivery end or mouth above the face of said throat-plate flared outwardly and inclined backwardly and downwardly, and a presser-foot opposed to said channel with a nose or toe portion outwardly flared and upwardly inclined correspondingly with the walls of said guide-blocks and forming with the latter a work-stretching channel. 30
3. A guiding device for sewing machines comprising a throat-plate, adjustable and spaced guide-blocks sustained in fixed relation with said throat-plate, and a presser-foot opposed to said guide-blocks and having a nose or toe portion forming with said throat-plate and guide-blocks a Y-shaped seam-guiding channel whose mouth is above the upper surface of said throat-plate and whose branches are flared outwardly and inclined backwardly and downwardly. 35
4. A guiding device for sewing machines comprising a throat-plate having a flat upper face with laterally spaced needle apertures and a longitudinal clearance slot in front of the same emerging into a tapered groove extending beyond the needle apertures, guide-blocks secured upon said throat-plate and spaced apart to afford a seam-guiding channel above said clearance slot and provided with divergently and backwardly inclined end-faces to form a flaring mouth for said channel, and a presser-foot having laterally spaced needle apertures and formed with a flat lower face or sole with a longitudinal groove extending from a point intermediate the needle apertures backwardly and with a nose or toe portion having upwardly inclined and angularly disposed work-smoothing faces corresponding substantially in inclination with the divergently inclined faces of said guide-blocks. 40
5. A guiding device for sewing machines comprising a throat-plate, adjustable and spaced guide-blocks sustained in fixed relation with said throat-plate, and a presser-foot opposed to said guide-blocks and having a nose or toe portion forming with said throat-plate and guide-blocks a Y-shaped seam-guiding channel whose mouth is above the upper surface of said throat-plate and whose branches are flared outwardly and inclined backwardly and downwardly. 45

In testimony whereof, I have signed my name to this specification, in the presence of two subscribing witnesses.

GEORGE S. GATCHELL.
